Patented Sept. 22, 1914.

UNITED STATES PATENT OFFICE.

JOHN W. BERCAW, OF HAMILTON, OHIO.

LAUNDRY-WASHING MACHINE.

REISSUED

1,111,126.

Specification of Letters Patent. Patented Sept. 22, 1914.

Application filed May 19, 1913. Serial No. 768,501

To all whom it may concern:

Be it known that I, JOHN W. BERCAW, a citizen of the United States, residing at Hamilton, in the county of Butler and State 5 of Ohio, have invented certain new and useful Improvements in Laundry-Washing Machines, of which the following is a specification.

My invention relates to an improvement 10 in a laundry clothes washing machine.

The object of my invention is to provide means effectively counteracting this entangling influence, and which will so manipulate the clothes as to prevent their inter-knotting, 15 whereby the time ordinarily required for manual disentanglement is saved and the garment-rending action of the machine eliminated.

Another valuable result produced is a distinct increment in the cleansing efficiency of 20 a machine embodying my improvement and a consequent material reduction in the time required for washing a given load.

The features of my improvement will be 25 more fully set forth in the description of the accompanying drawings, forming a part of this specification, disclosing the preferred embodiment of my invention, in which:—

Figure 1 is a front elevation of a washing 30 machine showing the inner cylinder door opened to exhibit my improvement as applied. Fig. 2 is a central vertical section through the inner cylinder. Fig. 3 is a perspective view of a detached clothes manipulating member partly in section. Fig. 4 is a 35 plan view, partly broken away, of a detached interior element of the clothes manipulating member.

The hollow, horizontal cylinders 1 and 2, 40 form the tub and washer of the machine. The tub is stationary and the perforated washer cylinder rotatable therein, each provided with a door in the usual manner, the inner cylinder door 3 being shown in Figs. 45 1 and 2. The inner cylinder is rotatably supported in the tub and may be suitably driven by connecting from a source of power to the driving wheel 20, and axial shaft 30, there being a clearance space between the 50 tub and inner cylinder.

The clothes manipulating and auxiliary washing member 4 is shown detached in Fig. 3, and applied to the interior of the perforated cylinder 2 in Fig. 1. It preferably 55 comprises a segmental imperforate base 5,

to which is attached the hollow rib 6, preferably formed of sheet metal, flanged at its adjacent ends 7 for attachment to the base 5. The chamber so formed is preferably wider at the base, having a rounded nose-like end to engage the clothes, projecting radially toward the cylinder axis. Within this chamber is placed a reciprocating valve-functioning member 8 hinged at the medial longitudinal line of the base by means of 60 suitable connections 40, its end terminating in the projecting end of said chamber, the walls of which are formed with inlet orifices 9 at the base, and the outlet orifices 10 in proximity to the clothes engaging end. The 65 unitary member so formed is suitably secured to the inner surface of the washing cylinder. When two members 4 are employed, as shown, I preferably dispose them diametrically, with the first member placed, 70 say 8 or 10 inches below the lower sill of the cylinder-door, so that the clothes will lie under said members in the bottom of the cylinder when brought to door-opening position. 75

I prefer the unitary structure illustrated, not only because of its convenient assembly into an organized machine, for factory manufacture, but because it can be shipped or applied as an accessory element to commercial machines of this general type, its use being obviously not restricted to a double cylinder washing machine, but being broadly applicable to various kinds of washing tubs. 80

Of course the segmental base could be 85 omitted, and the chamber formed by the sheet metal structure could be attached directly to the inner cylinder, but I prefer that the floor of this chamber should be imperforate in order to more reliably affect the 90 contemplated water flows through the orifices 9 and 10.

In practice, the wash water stands in the tub appreciably below the axial line, and the inner cylinder carries a proportionate load 100 of clothes, the inner cylinder being rotated periodically in opposite directions. Assuming the direction of a given rotation to be as indicated by the arrow, Fig. 2, the member 8 will have moved on its hinge to bring its 105 extremity against the inner surface of the lower or advancing chamber wall, forming an advancing water compartment 11 and a following water compartment 12, into which the water flows as the member dips below the 110

water level. The outer surface of the advancing wall and rounded nose will engage the clothes and move them in the general direction of rotation, lifting them above water level as it emerges. As the engaging member is raised from the bottom of the tub, the member 8 will swing to the other position. As compartment 12 is raised above the water level, the water will flow from the under orifices 10, striking the clothes, while in a little higher position the compartment 11 will be so tilted as to pour water from the uppermost orifices 10, thus not only tending to dislodge or disentangle the clothes, but materially increasing the cleansing efficiency by effectively dashing the wash water against the clothes when carried above the water level, serving also to increase the water agitation and inducing maximum water flows and currents. Preferably the end of the member 8 in its extreme position will alternately cover the orifices 10, first on one side and then on the other side of chamber 4, causing the orifices 9 to function generally as inlet, and the orifices 10 as outlet ports for the water. The clothes are thus not only prevented from entanglement, but are thoroughly subjected to additional washing

treatments, and agitation, with minimum knotting and rendering influences. 30

Having described my invention, I claim:—

1. An attachment for a washing machine comprising a base, or hollow rib thereon formed with water inlet and outlet orifices, and a single member hinged to the base 35 with its free end extending into the clothes-engaging end of said rib, and swinging from one side to the other of said hollow rib when the base revolves around an axis.

2. An attachment for a washing machine 40 comprising a segmental imperforate base, a hollow rib thereon formed with inlet and outlet orifices near the base and clothes-engaging rounded end respectively, and a single valve-functioning member pivoted to 45 an intermediate portion of the base within the chamber formed by said rib, with its free end movable from one side of the chamber to the other in relation to said orifices.

In witness whereof, I hereunto subscribe 50 my name, as attested by the two subscribing witnesses.

JOHN W. BERCAW.
